US00D959536S

(12) **United States Design Patent** (10) Patent No.: **US D959,536 S**
(45) Date of Patent: ** Aug. 2, 2022

(54) **CAMERA**

(71) Applicant: **GOOGLE LLC**, Mountain View, CA (US)

(72) Inventors: **Rochus Emmanuel Jacob**, San Francisco, CA (US); **Oliver Mueller**, San Francisco, CA (US); **Nicholas Unger Webb**, Menlo Park, CA (US); **Adam Duckworth Mittleman**, Redwood City, CA (US); **Jason Goulden**, Los Gatos, CA (US); **Kevin Edward Booth**, Mountain View, CA (US); **Tyler Scott Wilson**, San Francisco, CA (US); **Mark Kraz**, Santa Clara, CA (US); **Jeffrey Hui-Kwun Law**, San Francisco, CA (US); **William Dong**, Redwood City, CA (US)

(73) Assignee: **GOOGLE LLC**, Mountain View, CA (US)

(**) Term: **15 Years**

(21) Appl. No.: **29/677,161**

(22) Filed: **Jan. 17, 2019**

(57) **CLAIM**

The ornamental design for a camera, as shown and described.

DESCRIPTION

FIG. 1 is a top and front perspective view of a camera showing our new design;

FIG. 2 is a bottom and rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines depict portions of the camera in which the design is embodied that form no part of the claimed design. The dot-dash lines in FIGS. 1-6 represent the bounds of the claimed design and form no part of the claimed design.

1 Claim, 8 Drawing Sheets
